CLAIM

The ornamental design for a ball lacing with raised pebbled surface, as shown and described.

DESCRIPTION

FIG. 1 is a top plan view of a ball lacing with raised pebbled surface of the present design including dashed lines representative of a football.

FIG. 2 is an enlarged scale end elevational view of FIG. 1; FIG. 3 is an elevational view of the end opposite FIG. 2; FIG. 4 is a left side elevational view of FIG. 1;

FIG. 5 is an enlarged scale fragmentary views of FIG. 4; FIG. 6 is an enlarged scale fragmentary view of FIG. 1; FIG. 7 is an enlarged scale fragmentary view of FIG. 2; and, FIG. 8 is and enlarged scale fragmentary view of FIG. 3. The broken (dashed) lines shown in FIGS. 1 through 8 are included for the purpose of illustrating environmental elements only and form no part of the claimed design.
